ALFRED G. RAVENSCLAG, OF CHICAGO, AND FRANCIS P. TIKALSKY, OF LA GRANGE, ILLINOIS, ASSIGNEES TO WESTERN ELECTRIC COMPANY, INCORPORATED, OF NEW YORK, N. Y., A CORPORATION OF NEW YORK

EJECTING MECHANISM

Application filed December 26, 1929. Serial No. 416,448.

This invention relates to ejecting mechanisms, and more particularly to automatic ejecting mechanisms for die casting machines.

5 An object of the invention is to provide means for ejecting the castings from a die casting machine efficiently and with a minimum of effort on the part of the operator.

The mechanism constituting this invention is designed to be applied to a power driven die casting machine of the type where in a stationary die half and a movable die half cooperate to form a plurality of molds which, when the two die halves are brought together in cooperative relation, receive molten metal under pressure to form the castings, which castings are ejected by ejecting pins after the die halves are separated. The invention is more particularly applicable to the formation of castings having projecting portions or inserts of such length as to make ejecting by means of the usual ejecting mechanism difficult or impossible. In one embodiment of the invention, a plurality of 20 adjustable cam members actuate a stop member to move it, during withdrawal of the movable die half, into the path of a hand lever which is normally used to operate the ejecting mechanism, so as to cause the hand lever to be actuated by the power furnished to the machine rather than manually. When the castings have been partially ejected from the die, the stop member is automatically moved to inoperative position and the ejecting operation may be completed by hand if necessary.

Further objects of the invention will appear from the following description, taken in connection with the appended drawings, in which

40 Fig. 1 is a plan view of an apparatus embodying the invention, certain parts of the die casting machine being shown schematically;

45 Fig. 2 is a side elevation of the apparatus shown in Fig. 1, showing in broken lines the relative positions of the die halves when in closed relation;

50 Fig. 3 is a front view of the same, and

Fig. 4 is an enlarged elevational view of an article produced by the machine.

Referring more particularly to the drawings, the reference numeral 10 indicates a tie rod to which a plate 12 is adjustably fixed by means of clamps 13, 14. A stop member 16 is slidably mounted transversely of the plate 12 and is held against movement in any direction other than longitudinal by means of a bracket 18 adjustably secured to the plate 12 by means of bolts 20.

55 A pair of cam plates 21, 22 are adjustably secured to the movable bolster plate 24 of the machine by means of bolts 26, 27 which pass through slots 28, 29 formed in the cam plates and are designed to cooperate with a roller 30 carried by a stud 32 mounted at the end of the stop member 16. It will be seen that as the movable bolster plate 24 is reciprocated it will carry cam plates 21 and 22 past the roller 30, and the inclined cam surfaces of the plates will cause the stop member 16 to move alternately inwardly and outwardly.

60 The movable die half 34 of the machine is secured to the movable bolster plate 24 in spaced relation by means of four arms 36 secured respectively to the four corners of a die shoe 37 which is secured to the bolster plate, only one arm being shown in the drawings. It will thus be seen that as the movable 70 bolster plate is reciprocated by means (not shown) but known in the art, the die half 34 will alternately be moved to the position shown in full lines and to the position indicated at 38 in dotted lines in Fig. 2, where it 75 cooperates with a fixed die half 39 to form a plurality of molds for receiving molten metal.

80 An ejector plate 40 is movably mounted between die shoe and die half 34 by means of rods 42 slidably in bores (not shown) in the die shoe, and is designed to be reciprocated by means of a rack 44 fixed to the ejector plate and engaging a pinion 45 which is keyed to a shaft 46 journaled in the die shoe. A 85 hand lever 48 is keyed to shaft 46 to rotate it and thereby reciprocate the ejector plate 40. The ejector plate at its forward surface is provided with a plurality of ejector pins 50 which extend into cylindrical bores formed 90

in the movable die half for the purpose of ejecting the finished castings therefrom.

In the embodiment herein illustrated and described, the castings 52 being formed on the machine each consist of a previously formed insert 54 (Fig. 4) which may be of brass or other metal, or of other material, about which is formed a cast portion 55 of cast metal.

- 10 In the operation of the apparatus above described, the movable die half 34 being in the position shown in full lines in the drawings, the lever 48 is moved to the position indicated at 56 in dotted lines in Fig. 2, thereby retracting the ejector pins 50, and inserts 54 are inserted in the bores of the die half 34. The movable bolster plate 24 and movable die half 34, together with die shoe 37, cams 21, lever 48, ejector plate 40 and the parts 15 associated therewith, are then advanced, by known power means not shown, until lever 48 reaches the position 57 and the movable die half reaches the position indicated at 38 in Fig. 2, thereby bringing the two die halves 20 into operative relation. The molten metal is then introduced into the molds in the known manner, where it solidifies to form portions 55 about the inserts. As lever 48 approaches the position indicated at 57 in 25 Fig. 2, cam 21 engages roller 30 and moves stop member 16 outwardly until it lies in the path of lever 48. The movable bolster plate 24 and the other reciprocable parts are then retracted by the power means, and are moved 30 to the position shown in full lines in the drawings. During the retraction, stop member 16 contacts with lever 48 and causes it to rotate about shaft 46, thereby actuating rack 44 and causing the ejector pins 50 to force 35 the castings 52 out of their molds in the manner indicated at Fig. 2. As the reciprocating mechanism approaches the rearward limit of its stroke, cam 22 engages roller 30 and moves stop member 16 to inoperative position, whereupon the operator moves lever 48 forwardly if necessary to complete the 40 ejection of the castings, and then moves it rearwardly to the position indicated at 56 to permit the insertion of another set of inserts 45 preparatory to repeating the process. Because of the fact that it is a slow and difficult task to loosen the castings from the molds, and easy to move them farther out of the molds when they have once been loosened, 50 the above described apparatus considerably decreases the manual effort required to operate the machine and correspondingly decreases the time required to perform the cycle of operation.
- 55 While the invention has been described with particular reference to a specific embodiment, it may be embodied in other forms, and is not limited except by the following claims.

60 65 What is claimed is:

1. In a die casting machine having a reciprocating die member, means for reciprocating the die member, and means for ejecting the castings from the die member, including a lever pivotally related to the die member and operative to actuate the ejecting means and a stop member movable into contacting relation with the lever to actuate it and movable out of contacting relation with the lever to permit the lever to be manually manipulated. 70

2. In a die casting machine having a reciprocable die member, a stop member, means operated by the reciprocation of the die member for moving the stop member to operative and inoperative positions, and ejecting means controlled by the position of the stop member for ejecting the castings from the die member and manually operable when the stop member is moved to its inoperative position. 80

3. In a die casting machine having a reciprocable die member, a stop member, cam means operated by reciprocation of the die member for moving the stop member to operative and inoperative positions, and ejecting means adapted to be actuated by the stop member. 90

4. In a die casting machine having a reciprocable die mechanism, a stop member movable transversely of the direction of reciprocation of the die mechanism into operative and inoperative positions, cam means movable with the die mechanism for actuating the stop member, and ejecting mechanism comprising an element pivotally related to the die mechanism and adapted to cooperate with the stop member to eject the finished castings from the die mechanism. 95

5. In a die casting machine having a reciprocating die member movable through a cycle of operation, a stop member, ejecting means adapted to be actuated by the stop member upon movement of the die member, and means rendering the stop member operative during movement of the die member through one part of its cycle and inoperative during movement of the die member through another part of its cycle. 105

6. In a die casting machine having a stationary die member and a reciprocating die member, a stop member, manually operable ejecting means adapted to be actuated by the stop member, means for moving the stop member to an operative position during movement of the reciprocating die member toward the stationary die member, and means for moving the stop member to an inoperative position during movement of the reciprocating die member away from the stationary die member to permit manual manipulation of the ejecting means. 115

7. In a die casting machine having a stationary die member and a reciprocating die member, a stop member, ejecting means comprising a manually operable member reciprocating 120

roating with the reciprocating die member and adapted to be actuated by the stop member, means for moving the stop member into the path of the manually operable member

5 during movement of the reciprocating die member toward the stationary die member, and means for moving the stop member out of the path of the manually operable member during movement of the reciprocating

10 die member away from the stationary die member to permit manual manipulation of the ejecting means.

8. In a die casting machine having a stationary die member and a reciprocating die member provided with an aperture designed to receive inserts to be embedded in the casting, a stop member, ejecting means adapted to be actuated by the stop member upon movement of the reciprocating die member

15 20 and including an ejecting member movable in said aperture to force the insert and casting from the movable die member, and means rendering the stop member operative during movement of the die member in one direction and inoperative during movement of the die member in another direction.

In witness whereof, we hereunto subscribe our names this 14th day of December, A. D. 1929.

30 ALFRED G. RAVENSCHLAG.
FRANCIS P. TIKALSKY.
